DRAFT RIGGING

Emil H. Blattner, Rochester, N. Y., assignor to
The Symington-Gould Corporation, Rochester,
N. Y., a corporation of Maryland

Application July 11, 1933, Serial No. 679,951

15 Claims. (Cl. 213—26)

This invention relates to a particular form of cushioning mechanism and its arrangement with railway draft rigging so that a greater amount of travel and shock absorbing capacity may be provided for buffing movement of an associated coupler as compared with draft movement thereof.

The principal object of my invention, generally considered, is to provide a cushioning mechanism which may be double-ended for providing for the absorption of a greater amount of buffing forces than draft forces, as well as providing for a greater amount of coupler travel on buff than on draft, or may be single-ended for efficiently absorbing draft and buffing forces with the provision for a similar capacity for both purposes.

Another object of my invention is the provision of cushioning mechanism comprising a housing which may be described as "bottle shaped", at both ends or at one end, in that the neck or outer opening to said housing is smaller than the body thereof, whereby inwardly diverging friction surfaces are provided for engagement with wedge blocks which have their sharp ends disposed outwardly, said wedge blocks being separated by a spreader wedge which engages the adjacent surfaces thereof and urged toward the outer opening or neck of the housing by curved plate springs acting on an intermediate follower which, in turn, frictionally engages the inner surfaces of said wedge blocks.

A further object of my invention is the provision of cushioning mechanism involving a housing, an outer follower with a separate or combined spreader wedge and associated wedges acting through an intermediate follower on curved plate springs in such a manner that a relatively large movement of the outer follower and spreader wedge compresses the plate springs only a relatively small amount, whereby said springs may be of high capacity with provision for only relatively small compressibility.

Other objects and advantages of the invention relating to the particular arrangement and construction of the various parts will become apparent as the description proceeds.

Referring to the drawings illustrating my invention, the scope whereof is defined by the appended claims:—

Figure 1 is a partial side elevational view and partial vertical longitudinal sectional view of one form of my cushioning mechanism shown assembled with associated draft rigging, portions of the associated cheek plates and backstop being diagrammatically illustrated.

Figure 2 is a fragmentary plan of the mechanism shown in Figure 1, with portions in horizontal section.

Figure 3 is a transverse sectional view on the line 3—3 of Figure 1, looking in the direction 5 of the arrows.

Figure 4 is a longitudinal sectional view of a modified form of cushioning mechanism.

Figures 5 and 6 are transverse sectional views on the lines 5—5 and 6—6, respectively, of Figure 4.

Figure 7 is a fragmentary view, partly in side elevation and partly in longitudinal section, and showing another embodiment of my cushioning mechanism.

Figure 8 is a longitudinal sectional view on the line 8—8 of Figure 7, looking in the direction of the arrows.

Figure 9 is a partial side elevation and partial longitudinal sectional view illustrating another embodiment of my invention.

Figure 10 is a transverse sectional view on the line 10—10 of Figure 9, looking in the direction of the arrows.

Figure 11 is a longitudinal sectional view illustrating another embodiment of my cushioning mechanism, the manner of assembly of said mechanism being diagrammatically illustrated in dot-dash lines.

Figure 12 is a longitudinal sectional view illustrating another embodiment of my invention.

Figure 13 is a longitudinal sectional view illustrating the manner of assembly and disassembly of one embodiment of my invention.

Figure 14 is a longitudinal sectional view showing still another embodiment of my invention.

Figure 15 is a longitudinal sectional view illustrating a further form of my invention.

Figure 16 is an end elevational view of the embodiment of my invention illustrated in Figure 15.

Figure 17 is a fragmentary longitudinal sectional view illustrating another embodiment of my invention.

Figure 18 is a similar view illustrating a further embodiment of my invention.

Referring to the drawings in detail, like parts being designated by like reference characters, and first considering the embodiment of my invention illustrated in Figures 1, 2 and 3, there is shown a double-ended series friction draft gear 1 comprising a housing, casing or column member 2, with side walls 3 slotted, as indicated at 4, for receiving a draft key or other stop means 5 which extends through slots 6 in cheek plates 7 and 55.

associated draft sills 8, and holds the member or housing 2 against movement under the action of draft forces, while permitting rearward movement thereof under the action of buffing forces on account of the slots 6 being extended rearwardly of the normal position of the key 5.

In the present embodiment of my invention, the housing 2 is formed double "bottle" shaped, that is, it is open at both ends, as indicated at 10 9, the openings being restricted, as compared with the intermediate transverse section of the housing, a pair of opposite walls of said housing terminating in outwardly converging portions 10 and 10' which provide interior outwardly converging friction surfaces 11 and 11'.

Associated with the housing 2 are wedge blocks 12 and 12', generally triangular and approximately equilateral, in section, as shown in Figure 1, said blocks having outer faces 13 and 20 13' frictionally engaging the friction surfaces 11 and 11' on the housing at the respective ends, said surfaces 13 and 13' being respectively disposed at angles corresponding with the angularity of the surfaces 11 and 11', so that the inner surfaces 14 and 14' of said wedge blocks are disposed transverse to the longitudinal axis of the housing.

Disposed between the wedge blocks 12 and 12', at the ends of the housing, are spreader wedges 30 15 and 15' which, in the present embodiment, are combined with the followers 16 and 16' and complete the differential wedge arrangement. The wedge portion 15 of the combined member fits between the adjacent wedges 12 and has 35 inwardly converging friction surfaces 17 which engage corresponding friction surfaces 18 on the wedge blocks, and a corresponding arrangement exists at the rear end of the gear. In order to hold the parts in assembled relation and prevent 40 the spreader wedges 15 and 15' from getting out of position with respect to the wedge blocks 12 and 12', said spreader wedges and wedge blocks have normally abutting shoulders 19—19' and 20—20', respectively, which may be formed by 45 lugs on the spreader wedges, relatively narrow as compared with the width of said wedges, fitting in correspondingly narrow grooves in the wedge blocks, which serve to limit outward movement of the spreader wedges 15 and 15' with respect to the wedge blocks 12 and 12', which, of course, 50 assists the converging portions 10 and 10' in limiting movement of the wedge blocks 12 and 12' outwardly of the housing 2.

For opposing compression of and releasing the 55 gear or cushioning mechanism 1, there is provided a relatively large number or nest of curved plate springs 21 for the mechanism at each end of the housing, said springs being desirably curved concavely inward with the ends of the 60 inner spring of each group supported by transversely extending abutment portions 22 which are desirably integral with the housing. A few of the inner springs 21' are made narrower than the remainder, as shown in Fig. 2, to clear the 65 inwardly extending bosses or reinforcements around the slots 4 upon full compression of the springs 21 and 21'. If desired, liners 23 with longitudinally extending main portions 24, serving to guide said springs, and transversely bent 70 end portions 25, on which the spring ends slide when the gear is compressed, engaging the abutment portions 22 of the housing and desirably notched, as indicated at 26 to receive nibs 27, on the innermost springs, may be provided for 75 holding said springs in position, it being under-

stood that, if desired, all of the springs of each stack or nest may be correspondingly nibbed on the concave sides and provided with depressions corresponding with said nibs on the convex sides of said plates, to keep the springs in proper relative positions, as shown in the Suckow Patent No. 1,884,913.

In order to avoid gouging between the innermost spring plates 21 and the liners 23, the engaging edges of said liners are desirably ground 10 to provide slightly convex bearing surfaces, so that chiseling action cannot start. To further improve the operation, the surfaces of the transverse portions 25 of said liners, which are engaged by said plates, are coated or plated with 15 lead, desirably to a thickness of about one sixtieth fourth of an inch.

Disposed between the convex sides of the spring nests and the associated wedge blocks 12 and 12' are intermediate followers 28, said followers receiving release pressure direct from the convex sides of the springs and engaging the inner faces or sides of the wedge blocks 12 and 12'. All of the friction faces or one of each pair of friction faces may, if desired, be provided with lead 25 inserts 29 to eliminate sticking and provide for smooth operation.

The intermediate follower 28 includes a wear plate member 70 providing an outer or friction surface for the follower 28 adapted to be frictionally engaged by the transversely disposed inner surfaces 14 and 14' of the wedge blocks 12 and 12', respectively. The spring contacting surface 59 of the follower 28 is cylindrically concave about radii preferably larger than the normal curvature of the springs 21 and 21' so that when the springs are compressed under a predetermined travel the final curvature of the springs will conform to the curvature of the surface 59. The reason for such a curvature on the follower is that with a flat follower and with spring travel determined so that the leaves theoretically do not go quite flat the actual shape of the compressed spring is not a single curve of slight final crown, but a triple curve. 45 The outer third of the spring retains a portion of the original curvature, while the middle third has been urged beyond flat and curves in the opposite direction, thereby giving two points of contraflexure. The disadvantage of so curving 50 a plate spring or stack of springs is that while the resistance is augmented by the provision of the triple curvature, because there are virtually then two very short spans instead of a full length span, yet the medial portion is over- 55 stressed by being urged beyond the theoretical travel and forces to reverse its direction of curvature. The result of thus stressing the spring, or springs, is that the fatigue life is relatively low.

Experiment has shown that by starting the 60 springs with a much higher initial camber, using a curved follower as indicated at 28, and leaving the springs compressed with a correspondingly higher crown, said springs do not adopt the triple curve above referred to, and the actual fiber 65 stresses are, therefore, low. For otherwise identical groups the springs 21 have the same or a higher capacity and a longer life.

Although the mechanism at the two ends of the housing 2, that is, the housing construction, 70 the springs 21, the intermediate followers 28, the wedge blocks 12 and 12', and the spreader wedges 15 and 15' may be identical at both sides of the transverse central plane of the mechanism, yet, in the present embodiment, I have shown the con- 75

struction at the front end sufficiently different, by making the spreader wedge portion 15 blunter, and the angularity of the friction surfaces 11 adjacent the front end of the housing 2 less, than the corresponding portions adjacent the rear end, that the travel of the front follower portion 16 before it engages the front end of the housing is less than the travel of the rear follower portion 16' before it goes solid against the housing 2.

The operation of the gear of the present embodiment may be as follows, although it will be understood that, if desired, said mechanism may be utilized as an ordinary single-ended gear with the entire capacity brought into action under both draft and buffing forces. When draft force is applied to the associated coupler 30, said force is transmitted from said coupler to the associated yoke 31 through the connecting key 32, thereby effecting a compression of the rearmost mechanism of the gear by forward movement of the rear follower 16', forcing the rear spreader wedge 15' into the housing 2, carrying the rear wedge blocks 12' along at a slower rate and, in turn, pushing the rear intermediate followers 28 and 70 into the housing, and flattening out the associated curved plate springs 21 which rest on the liners, it being understood that the housing 2 is prevented from forward movement by the connecting draft key 5, which extends through rearwardly elongated slots 32' in the arms of the yoke 31 and engages the cheek plates 7 at the front ends of the slots 6 therein.

Under the action of buffing force, however, the coupler 30 engages the front follower 16 and pushes the associated spreader wedge portion 15 between the front wedge blocks 12, moving said wedge blocks and associated intermediate followers 28 and 70 rearwardly at a slower rate to compress or flatten out the associated curved plate springs 21 which rest on the liners 23 and abutment portions 22 of the housing.

On account of the rearward elongation of the slot 6 in the cheek plates 7 and sills 8 of the associated railway vehicle, the housing 2 moves rearwardly during the compression of the mechanism of the front end, causing a corresponding compression of the mechanism at the rear end, against the rear portion of the yoke 31 and associated backstop 33, except that if the travel or capacity of the front mechanism is less than that of the rear mechanism, it may go solid before full compression of said rear mechanism. It will, therefore, be seen that full compression of the gear is permitted under the action of buffing force, not only providing for increased buffing capacity, but for a coupler travel equal to the sum of the travel permitted by the friction elements at each end of the gear. Although I have shown a gear or cushioning mechanism in which the travel at the front end is less than that at the rear end, it will be understood that this is not essential in accordance with the broad aspect of my invention, as the part of the gear in Fig. 2 which is not shown may correspond with that shown.

Referring now to the embodiment of my invention illustrated in Figures 4, 5 and 6, I have provided a single-ended friction draft gear 1a comprising a housing or column member 2a with both pairs of opposite side walls 3a and 34 slotted, as indicated at 4a and 35, respectively, for receiving an associated draft key (not shown) for connecting the housing to the associated cheek plates and draft sills in a manner similar to the connection illustrated in Figure 2. On account of

having the housing 2a slotted, as shown, it, in effect, functions as a combined housing and front follower. By having not only the side walls but also the top and bottom walls slotted for receiving a draft key, with the corresponding ends of the slots lying in the same transverse planes, the housing need not be increased in length and may be arranged horizontally or vertically between the sills for use with either a vertical yoke or a horizontal yoke, as desired, the slots not receiving the draft key functioning as inspection and lightening apertures.

In the present embodiment of my invention, the housing 2a is formed "bottle" shape, that is, it is open at one end, as indicated at 9a, said opening being restricted, as compared with the remaining section of the housing, a pair of opposite walls 34 of the housing terminating in outwardly converging portions 10a which provide interior outwardly converging friction surfaces 11a.

Associated with the housing 2a are wedge blocks 12a generally triangular in section, as shown in Figure 4, said blocks having outer faces 13a frictionally engaging the friction surfaces 11a on the housing, said surfaces 13a being disposed at angles corresponding with the angularity of the surfaces 11a so that the inner surfaces 14a of said wedge blocks are normally disposed transverse to the longitudinal axis of the housing. The laterally outermost corners of the blocks are desirably notched out, as in the preceding embodiment and certain of the succeeding embodiments, as indicated at 67, to clear the liners 23a and the liner engaging ribs 68.

Disposed between the wedge blocks 12a is a spreader wedge 15a which completes the differential wedge arrangement. The spreader wedge 15a fits between the adjacent wedges 12a and has inwardly converging friction surfaces 17a which engage corresponding friction surfaces 18a on the wedge blocks. In order to hold the parts in assembled relation and to prevent the spreader wedge 15a from getting out of position with respect to the wedge blocks 12a, said spreader wedge desirably has extensions 36, relatively narrow as in the preceding embodiment, to avoid any large loss in the friction areas, fitting in corresponding pockets 37 in the wedge blocks 12a, which construction provides for the normally abutting shoulders 19a and 20a on the spreader wedge and wedge blocks, respectively, and the engagement serves to limit outward movement of the spreader wedge 15a which, of course, also limits corresponding movement of the wedge blocks 12a outwardly of the housing 2a. The foregoing construction permits the assembly of the spreader wedge 15a, after the remaining parts are in the housing, by pushing it in place between the wedge blocks 12a, until the shouldered portions 19a and 20a snap into engagement with one another, as in the preceding and certain of the succeeding embodiments.

For opposing compression of and releasing the gear or cushioning mechanism 1a, there is provided a relatively large number or stack of curved plate springs 21a, said springs being desirably curved concavely inward, with the ends of the inner spring resting on transversely extending abutment portions 22a, which abutment portions 70 may also serve to define the adjacent ends of the slots 35 and are, of course, desirably integral with said housing. If desired, liners 23a with longitudinally extending main portions 24a serving to guide the springs and transversely bent 75

end portions 25^a engaging the abutment portions 22^a of the housing and desirably notched, as indicated at 26^a , to receive nibs 27^a on the innermost springs, may be provided for holding said 5 springs in position, it being understood that the springs 21^a are desirably formed like the springs 21 of the preceding embodiment, and the liners may likewise be coated or plated with lead.

Disposed between the convex side of the spring 10 stack and the associated wedge blocks 12^a is an intermediate follower 28^a , including a spring steel follower wear plate 38 , said follower receiving release pressure from the convex sides of the 15 springs and frictionally engaging the inner faces or sides of the wedge blocks 12^a . Lead inserts 29^a may be provided, as in the preceding embodiment. The wear plate 38 is desirably normally curved to cooperate with the spring stack and increase the total travel. Some of its individual 20 travel provides a means for returning the gear parts to pocket length, when the main springs 21^a lag due to friction between the leaves thereof. In due course, such friction would be relieved, and the main springs would regain their original 25 camber, subject only to the relatively small resistance of the outer curved combination plunger release spring, and interior follower wear plate 38 .

The operation of the gear of the present embodiment may correspond with that of the rear mechanism and slotted portion of the gear housing of the preceding embodiment, it being understood that the gear 1^a may be used with a rear follower 16^a and embraced by a yoke 31^a associated with a backstop 33^a and all disposed between associated draft sills (not shown), the front end of the housing 2^a being engaged by the rear portion of an associated coupler or drawbar 30^a , whereby said gear is fully operable 40 under both buff and draft, as will be understood.

Referring now to the embodiment of my invention illustrated in Figures 7 and 8, there is provided a selective travel draft gear 1^b corresponding substantially with that illustrated in 45 Figures 1, 2 and 3, except that instead of having slots 4^b only for receiving a key extending the short way through the housing 2^b , we also have slots 35^b for receiving a key extending the long way through the housing, as in the embodiment 50 of Figures 4, 5 and 6. Further differences reside in the fact that the wedge blocks 12^b and the combined center wedge and follower 15^b at each end of the gear are maintained assembled with the housing by a pin 39 extending into notches 40 in the blocks 12^b through a slot 41 in the spreader wedge 15^b , and with its ends extending into receptacles or pockets 42 and 43 in the end portion of the housing 2^b . The pin 39 is desirably prevented from loss or undesired 55 removal by having the outer portion of the pocket 42 partially closed by an apertured wall 44 , and the outer portion of the pocket 43 closed after application of the pin 39 by a desirably flat retainer 45 inserted through slots and bent to locked position after application, like the retainer 45^c in Fig. 9. The slot 41 in the wedge 15^b is sufficiently elongated to permit the desired compression of the gear, while limiting outward movement thereof beyond the position illustrated in 60 Figures 7 and 8.

In the present embodiment, each intermediate follower 28^b includes a spring plate wear member 38^b , curved when free of compression, and functioning like the plate 38 of the embodiment of Figures 4, 5 and 6, except that it is shown as 70

lighter and provides the outer or friction surface for the follower 28^b and is engaged by the wedges 12^b , rather than being the inner element of said follower and engaging the plate springs 21^b . Except as specifically described, the gear may correspond substantially with that of Figures 1, 2 and 3, it being understood that although a little more than half of the gear is illustrated, the parts not shown desirably correspond with the parts shown. As in Figures 1, 2 and 3, the center 10 wedges 15^b may have integral follower portions 16^b .

Referring now to the embodiment of my invention illustrated in Figures 9 and 10, I have provided a single-ended gear 1^c like that of Figures 4, 5 and 6, but without the slotted portions functioning as a front follower. Instead of said follower portion, the gear 1^c has the forward or closed portion of the housing 2^c restricted in cross-section, as indicated at 46 , to provide a pocket receiving the double coil helical spring 47 between the end wall 48 of the housing 2^c and an intermediate follower 49 . Movement of the follower 49 for compressing the spring 47 is limited by shoulders 50 engaged by the side portions of 20 said follower when the spring 47 has been compressed to the desired extent. The curved plate springs 21^c , as in previous embodiments, engage liners 23^c which, of course, move with the follower 49 as the gear is compressed or allowed to 30 release. The remainder of the mechanism, including the other intermediate follower 28^c , the spring wear plate 38^c , the wedge blocks 12^c , the center wedge 15^c , the pin 39^c , and the retainer 45^c , may correspond generally with that of Figures 7 and 8, except that, in the present embodiment, the center wedge 15^c is shown separate from the associated follower 16^c .

Referring now to the embodiment of my invention illustrated in Figure 11, I have provided 40 a relatively short "bottle" type of gear, single-ended like those of Figures 4, 5, 6, 9 and 10, but shorter in that the liners 23^d of the gear 1^d are supported directly on the end or front wall 38^d of the housing 2^d , instead of on intermediate abutment portions. In the present embodiment, the liners 23^d are of double thickness, or each comprises two parts, an inner part 51 and an outer part 52 . The inner liner member 51 is desirably made longer and bent where it extends beyond 50 the outer liner 52 at about 45° , so that when the follower 28^d is entered, it cannot possibly foul the liner. The transversely bent portion of the liner 51 is, as in previous embodiments, slotted, as indicated at 26^d , to receive the locating nibs 27^d of the plate springs 21^d . The outer liner 52 need not be notched, but lead is desirably applied between the transversely extending flanges of the associated liners, as by plating, for a purpose previously explained in connection with the 60 description of Figures 1, 2 and 3. Except as specifically described in connection with the present embodiment, the same may correspond substantially with that of Figures 9 and 10. The manner of entering the follower 28^d and its associated spring plate wear member 38^d , curved when free of compression, is illustrated diagrammatically by dot-and-dash lines.

Referring now to the embodiment of my invention illustrated in Figure 12, a short "bottle" 70 type gear 1^e has been provided corresponding generally with that of Figure 11, except that single liners 23^e are employed as in the embodiment of Figures 1, 2 and 3, rather than double liners, as in the embodiment of Figure 11. Further dif- 75

ferences reside in the fact that the intermediate follower 28^e has no wear member, and the wedge blocks 12^e and center wedge 15^e are maintained assembled by a longitudinal bolt 39^e rather than a transverse pin, said longitudinal bolt desirably having its head 53 countersunk in the follower 28^e and a nut 54 applied to the end which extends into the center wedge 15^e. Two washers 55 may be employed between the nut and the adjacent portion of the wedge 15^e. One of the washers 55 acts normally and the other is formed of destructible material, such as lead or hard wood, to hold the gear initially to less than pocket length to facilitate application. During use the destructible washer is eliminated, letting the gear assume its normal length. Except as specifically described, the construction may correspond generally with that of Figure 11.

Referring now to the embodiment of my invention illustrated in Figure 13, a relatively short "bottle" type gear 1^f is disclosed, which gear corresponds generally with that of Figure 11, except that single rather than double liners 23^f are employed, as in the embodiment of Figure 12, in a housing 2^f, and the center wedge 15^f, the associated integral follower 16^f and the associated wedge blocks 12^f correspond with those of the embodiment of Figures 1, 2 and 3. The drawings illustrate how the parts are assembled and disassembled by means of a plunger 56 and press 57. The assembly of the parts involves positioning all parts in the housing except the center wedge 15^f. The assembly plunger 56 is then inserted through the aperture 58 in the center wedge 15^f and the springs 21^f compressed through the follower 28^f and spring wear member 38^f to approximately seventy-five per cent. of their full compressibility, at which time the center wedge 15^f will fall into place. Disassembly is accomplished in reverse order.

Referring now to the embodiment of my invention illustrated in Figure 14, a gear 1^g is disclosed corresponding substantially with that of Figures 4, 5 and 6, except that instead of having an intermediate follower and spring plate wear member, I have an intermediate follower 28^g which is similar to the follower 28 disclosed in Figures 1 to 3, inclusive, the spring contacting surface of which is cylindrically concave, as indicated at 59', to conform with the final curvature of the spring pack 21^g when fully compressed under the predetermined travel. In the present structure it will be observed that the wear plate 10 of the embodiment of Figures 1 to 3 has been omitted, the wedge blocks being adapted to slidably engage the intermediate follower 28^g. Except as specifically described, the construction of the gear 1^g may correspond with that of Figures 4, 5 and 6, except that the center wedge 15^g is shown integral with the follower 16^g, as in the embodiment of Figures 1, 2 and 3.

Referring now to the embodiment of my invention illustrated in Figures 15 and 16, I have disclosed a gear 1^h relatively short, like those of Figures 11 and 12, but otherwise corresponding substantially with the gear of Figures 4, 5 and 6, except that the means functioning as a center plunger or wedge is split into two wedges 15^h and a T-shaped intermediate follower 28^h is employed, providing a central fin 60 against which the separated halves 15^h of the plunger bear, thereby producing additional frictional resistance. The fin 60 is desirably reinforced at its sides by generally triangular gusset portions 61 which extend to the main or follower portion 28^h.

Except as specifically described, the construction may otherwise correspond generally with the embodiment of Figures 4, 5 and 6.

Referring now to the embodiment of my invention illustrated in Figure 17, a gear 1^k is fragmentarily disclosed corresponding generally with the short "bottle" type gears of Figures 11 and 12, with special provision to reduce wear and gouging from the sharp edges of the leaf springs involving the employment of a spring wear piece 61', desirably of material heavier than that of the leaf springs 21^k, and of relatively small camber, so that it comes into action only a short distance before the gear closes, tending to increase the capacity of the gear sharply toward the end of its travel. The spring leaves are shown provided with nibs 27^k received in corresponding slots or depressions 62 in the wear plate 61'. Except as specifically described, the construction may correspond with either of the embodiments of Figures 11 and 12.

Referring now to the embodiment of my invention illustrated in Figure 18, a gear 1^m is fragmentarily illustrated, the portion not shown corresponding with one of the preceding embodiments such as those of Figures 11 and 12. In the present embodiment, I employ a wear plate 61^m, as in the preceding embodiment, said plate, however, not having its ends bent substantially at right angles like that of Figure 17, the ends being merely ground off, as indicated at 66, to avoid gouging between said plate and the end wall 48^m of the housing 2^m. A stack of plate springs 21^m, only partially illustrated, may be employed, having nibs 27^m, with those on the innermost plate received in corresponding depressions or pockets 62^m in the wear plate 61^m. The plate 61^m, in the present embodiment, and the plate 61' of the preceding embodiment, by extending beyond the stack of springs associated therewith and interlocked with said springs, retains the sharp edges of the springs out of engagement with the walls of the housing, as well as preventing the edges of the inner spring from gouging the end wall or spring abutment portions of the housing.

From the foregoing description, taken in connection with the accompanying drawings, it will be seen that I have devised what I call a "bottle" type gear which may be double-ended for selective travel purposes, or single-ended to interchange with the conventional friction draft gear. The gear comprises a housing carrying a relatively large number of curved leaf springs, with the provision of a differential wedge arrangement which may allow a coupler movement of two and five-eighths inches for a plate compression of one inch. A precurved wear plate and plunger release spring may be employed in connection with any type of gear illustrated, although not shown on all types, as will be understood, said plate being either on the outside or wedge-block-adjacent face of the follower, or on the inside or spring-adjacent face of said follower. Gouging of the springs on the interior surfaces of the housing may be avoided by interior liners, either single or double, with the employment of lead lubricant to minimize wear and scoring. If desired, a helical spring may be employed in series with the plate springs, thereby providing for an easy initial compression of the gear. The wedges may be maintained assembled with the housing in various ways, as by interlocking shoulders, a transverse pin, or a longitudinal pin or bolt. Assembly and disassembly of the mechanism is desirably accomplished by means of a press and

plunger, as described. The double-ended gear may be symmetrical or unsymmetrical, thereby providing for exactly double the shock absorbing capacity for buffing forces, as compared with 5 draft forces, or some other ratio. Increased capacity may be provided by the use of a T-shaped follower, with a central fin engaged by separated portions of a central wedge. The fatigue life of the curved plate springs may be increased by the 10 employment of a follower with a cylindrically concave spring engaging surface, which follower may be employed with any one, or all, of the embodiments disclosed.

Although preferred embodiments of my invention 15 have been illustrated, it will be understood that additional modifications may be made within the spirit and scope of the appended claims.

I claim:—

1. A double-ended draft gear comprising a 20 housing with longitudinal walls having end portions extending diagonally inward to decrease the end size and provide outwardly converging friction surfaces at both ends, wedge blocks at each end of the housing with outer faces frictionally 25 engaging said surfaces and also provided with surfaces inwardly converging with respect to one another, a spreader wedge at each end of the housing acting between said blocks and having corresponding friction faces engaging said inwardly converging friction faces on the blocks, a 30 set of nested plate springs adjacent each end of the housing, concavely curved toward and supported by portions adjacent the center thereof, and an intermediate follower disposed between 35 each set of springs and the adjacent wedge blocks with its inner surface concave about radii larger than the normal curvature of said springs and engaging the convex outer surface of the outer one of said springs, and its outer surface frictionally engaged by the inner surface of said 40 wedge blocks.

2. A double-ended draft gear comprising a housing with longitudinal walls having end portions extending diagonally inward to decrease the 45 end size and provide outwardly converging friction surfaces at both ends, wedge blocks at each end of the housing with outer faces frictionally engaging said surfaces and also provided with surfaces inwardly converging with respect to one 50 another, a spreader wedge at each end of the housing acting between said blocks and having corresponding friction faces engaging said inwardly converging friction faces on the blocks, an end follower associated with each spreader 55 wedge, a set of nested plate springs adjacent each end of the housing, concavely curved toward and supported by portions adjacent the center thereof, an intermediate follower disposed between each 60 set of springs and the adjacent wedge blocks with its inner surface concave about radii larger than the normal curvature of said springs and engaging the convex outer surface of the outer one of said springs, and its outer surface frictionally engaged by the inner surface of said wedge blocks, 65 the spreader wedge at one end being blunter than that at the other, and its follower normally spaced a distance from the housing different from that of the follower at the other end to provide for different travels of the mechanisms at the two 70 ends of the gear.

3. A cushioning mechanism comprising a housing with longitudinal walls having end portions extending diagonally to decrease the end size and provide outwardly converging friction surfaces, 75 wedge blocks with outer faces frictionally engag-

ing said surfaces and provided with faces inwardly converging with respect to one another, spreader wedge means acting between said blocks and having corresponding friction faces engaging said inwardly converging friction faces on the blocks, said housing being provided with transverse abutment portions disposed inwardly of said blocks, a set of nested plate springs concavely curved toward said abutment portions and with the ends of the inner spring supported 10 thereby, and follower means disposed between said set and the wedge blocks having a surface concave about radii larger than the normal curvature of said springs and acting on the convex outer surface of the outer one of said springs 15 and an additional surface on said follower means frictionally engaged by the inner surfaces of said wedge blocks, the construction comprising means for preventing undesired disconnection between said spreader wedge and the housing. 20

4. A cushioning mechanism comprising a housing with longitudinal walls terminating in end portions provided with outwardly converging friction surfaces, a differential wedge assembly comprising wedge blocks generally equilateral triangular in section associated with said housing adjacent said friction surfaces to provide for a longitudinal movement of a central wedge considerably greater than that of associated side wedges, a set of nested plate springs concavely 25 curved toward a portion of the housing remote from the friction surfaces, and follower means disposed between said set and the wedge assembly and provided with an inner arcuate surface concave about radii greater than the normal 30 curvature of said springs and an outer surface frictionally engaged by some of the wedges comprising said assembly, the construction comprising means for preventing undesired disconnection of the wedge assembly and housing. 40

5. A cushioning mechanism comprising a housing with longitudinal walls terminating in end portions provided with outwardly converging friction surfaces, wedge blocks with outer faces frictionally engaging said surfaces and also provided with faces inwardly converging with respect to one another, spreader wedge means acting between said blocks and having corresponding friction faces engaging said inwardly converging friction faces on the blocks, said housing being provided with transverse abutment portions disposed inwardly of said blocks, a set of nested plate springs concavely curved toward said abutment portions and with the ends of the inner spring supported thereon, follower means disposed between said set and the wedge blocks, and including a follower member and a wear plate and wedge release spring curved, when free of pressure, engaging one face of said follower member and exerting pressure on the springs and blocks to facilitate release of the mechanism the construction comprising means for preventing undesired disconnection between said spreader wedge and wedge blocks. 55

6. A cushioning mechanism embodying a housing with longitudinal walls terminating in end portions provided with outwardly converging friction surfaces, wedge blocks with outer faces frictionally engaging said surfaces and provided with faces inwardly converging with respect to one another, center wedge means acting between said blocks and having corresponding friction faces engaging said inwardly converging friction faces on the blocks, said housing having means providing abutments, a set of plate springs concavely 70 75

curved toward said abutments and with the ends of the inner spring supported thereby, plates disposed between opposite side edges of said springs and the adjacent walls of said housing to avoid 5 wear on said walls, the inner end portions of said plates being angularly disposed to overlie said abutments and be slidably engaged by the ends of said inner spring, and follower means disposed between said set and the wedge blocks, acting 10 on the convex outer surface of the outer one of said springs and frictionally engaged by the inner surfaces of said wedge blocks, the construction comprising means for preventing undesired disconnection between said center wedge 15 and wedge blocks.

7. Cushioning mechanism comprising a housing with longitudinal walls terminating in end portions provided with outwardly converging friction surfaces, wedge blocks with outer faces frictionally engaging said surfaces and provided with other faces inwardly converging with respect to one another, a center wedge acting between said blocks and having corresponding friction faces 20 engaging said inwardly converging friction faces on the blocks, said housing being provided with transverse abutment portions disposed inwardly of said blocks, a follower disposed outwardly of said abutment portions and adapted to engage the same upon compression of the mechanism, 25 coil spring means received in said housing inwardly of said abutment portions, a set of plate springs concavely curved toward said follower and with the ends of the inner spring acting thereon, and follower means disposed between 30 said set and the wedge blocks, acting on the convex outer surface of the outer one of said springs and frictionally engaged by the inner surfaces of the wedge blocks, the construction comprising means for preventing undesired disconnection 35 between said center wedge and the housing.

8. Cushioning mechanism comprising a housing with longitudinal walls terminating in end portions provided with outwardly converging friction surfaces, wedge blocks with outer faces frictionally engaging said surfaces and provided with faces inwardly converging with respect to one another, center wedge means acting between said blocks and having corresponding friction faces 40 engaging said inwardly converging friction faces on the blocks, relatively narrow tongues on said center wedge means fitting in corresponding grooves in said wedge blocks and providing normally engaging shoulders on said center wedge means and wedge blocks to only limit movement 45 of said center wedge means outwardly of the housing, a set of nested plate springs concavely curved away from said wedge blocks and supported by a portion of the housing, and follower means disposed between said set and said wedge 50 blocks, acting on the convex outer surface of said set, and frictionally engaged by said wedge blocks.

9. Cushioning mechanism comprising a housing with longitudinal walls terminating in end portions provided with outwardly converging friction surfaces, wedge blocks with outer faces frictionally engaging said surfaces and provided with faces inwardly converging with respect to one another, other wedge blocks acting between said blocks and having corresponding friction faces 55 engaging said inwardly converging friction faces on the blocks, a set of plate springs supported on a portion of said housing, and a follower disposed between said plate springs and wedge blocks, said follower having a longitudinally extending web disposed between and frictionally en-

gaged by said other wedge blocks for increasing the capacity of the mechanism.

10. Cushioning mechanism comprising a housing with longitudinal outer walls terminating in diagonally extending end portions provided with outwardly converging friction surfaces, wedge blocks with outer faces frictionally engaging said surfaces, and other faces inwardly converging with respect to one another, a spreader wedge acting between said blocks and having corresponding friction faces engaging said inwardly converging friction faces on the blocks, a set of nested plate springs of uniform length and concavely curved away from said blocks, said housing having end abutments on which edges of 15 the end spring, on the concave side of the nest, frictionally slide when the mechanism is operated and follower means disposed between the outer spring and said wedge blocks, said follower means having an outer surface slidably engaged by 20 said wedge blocks and a surface, engaging said outer spring, which is concave about a larger radius than the normal curvature of said spring, in order to avoid reversal of curvature under load and consequent decrease in the fatigue life. 25

11. Cushioning mechanism comprising a housing provided with inclined friction surfaces, friction means slideable on said surfaces and adapted for longitudinal and transverse movement, an element movable in said housing, 30 a set of nested plate springs concavely curved away from said element, and abutments on said housing normally slidably engaged by the ends of the spring at the concave end of said set, said element having a flat outer 35 friction surface engaged by said friction means and an inner surface engaging the adjacent spring and concavely curved about a radius larger than that of the normal curvature of said spring, in order to avoid reversal of curvature under load 40 and consequent decrease in the fatigue life.

12. Cushioning mechanism comprising a housing with two pairs of longitudinal walls one pair of which terminates in end portions provided with friction surfaces, wedge blocks frictionally 45 engaging said surfaces, a wedge acting on said wedge blocks, a set of plate springs concavely curved toward and supported by abutment portions on said housing inwardly of said blocks, liner plates interposed between opposite side 50 edges of said springs and adjacent wall of said housing, said liner plates having an angularly disposed portion bearing against said abutments and slidably engaged by the inner plate of said springs, and a follower disposed between said 55 springs and the wedge blocks, with its inner surface engaging the convex outer surface of said springs and its outer surface frictionally engaged by said wedge blocks. The construction comprising means for preventing undesired disconnection 60 of the parts from the housing, said housing having a portion remote from said friction surfaces, beyond the portions supporting said springs, and formed with a slot for the reception of a draft key. 65

13. The method of assembling the elements of a friction draft gear involving a housing with a restricted outer opening providing outwardly converging friction surfaces, wedge blocks engaging said surfaces, a center wedge having an aperture 70 extending therethrough, curved plate springs and an intermediate follower, comprising positioning of the parts in the housing except the center wedge, inserting means through the aperture in the center wedge, and compressing the springs 75

through the follower by said means until said center wedge falls into place.

14. Cushioning mechanism comprising a housing with inclined friction surfaces, friction means 5 slidable on said friction surfaces, toward and away from the center of said housing, a plurality of nests of curved plate springs, with their concave sides facing one another and their convex sides facing said friction means, said means comprising surfaces engaging the outer springs of 10 said nests, said surfaces being concave about radii larger than the normal curvature of said springs, in order to avoid reversal of curvature under load and consequent decrease in the fatigue life, and 15 means provided between said springs, on which the edges of the innermost springs at the concave sides thereof slide.

15. Cushioning mechanism embodying a housing 20 with longitudinal walls terminating in end portions provided with outwardly converging friction surfaces, wedge blocks with outer faces frictionally engaging said surfaces and provided

with additional faces inwardly converging with respect to one another, a center wedge acting between said blocks and having corresponding friction faces engaging said inwardly converging faces on the blocks, a set of plate springs concavely curved toward abutment portions formed in said housing inwardly of said blocks, liner plates interposed between opposite side edges of said springs and adjacent walls of the housing, said liner plates having an angularly disposed portion bearing against said abutments and slidably engaged by the inner plate of said springs, follower means interposed between said spring set and wedge blocks having an inner surface concave about radii larger than the normal curvature 15 of said spring set acting on the concave outer surface of the spring set and an outer surface frictionally engaged by said wedge blocks, the construction providing means for preventing undesired disconnection between said center wedge 20 and wedge blocks.

EMIL H. BLATTNER.

CERTIFICATE OF CORRECTION.

January 4, 1938.

Patent No. 2,104,114.

EMIL H. BLATTNER.

It is hereby certified that error appears in the printed specification of the above numbered patent requiring correction as follows: Page 7, second column, line 59, claim 12, for the words "blocks. The" read blocks, the; and that the said Letters Patent should be read with this correction therein that the same may conform to the record of the case in the Patent Office.

Signed and sealed this 22nd day of February, A. D. 1938.

Henry Van Arsdale,
Acting Commissioner of Patents.
